UNITED STATES PATENT OFFICE.

JOSEPH A. HUDNER, OF SAN JUAN, CALIFORNIA.

LATCH MECHANISM.

Application filed January 21, 1924. Serial No. 687,518.

This invention relates to improvements in latches or locks and more particularly to door latches for steam shovel dippers.

The primary object of this invention is to provide a gravity latch for steam shovels of the so-called "dipper type" which is durable, simple in operation and positive in action.

Another object is to construct a latch of this character that will stand considerable rough usage without jamming or sticking when actuated to dump the load.

A further object is to provide a latch constructed to be actuated by a pivotal arm having considerable leverage, said latch being fulcrumed close to the pivotal point of said arm, so that the dumping of the load is accomplished by a slight pull at the outer end of the arm.

Other objects and advantages and features of my invention will appear with reference to the subjoined specification and the accompanying one sheet of drawings, in which:

Figure 1 is a rear elevation of an ordinary type of steam shovel dipper, showing the door in closed position and my latch in place as it appears when in latched position.

Figure 2 is a bottom view of a fragment of the rear end of the dipper shown in Fig. 1 with the door in place and the latch in latched position against the front thereof.

Figure 3 is a vertical sectional detail taken at line 3—3 of Fig. 1 of the rear end of the dipper and door with my latch in latched position.

Figure 4 is a cross section taken at line 4—4 of Figs. 1 and 3 and showing the latch bolt housing, guideway and latch bolt therein.

Referring more particularly to the drawings and especially to Fig. 1 thereof, 10 designates an ordinary steam shovel dipper provided with the customary swinging door 11 hingedly connected to the rear end by the hinged arms 12. The door 11 fits snugly against the rear edge 13 of the dipper and the dipper bottom 14 is provided with a frontal projection or latch member 15 extending therefrom, which member is provided with a square opening 16 located in alignment with and adapted to receive the latch bolt 17.

The latch bolt 17 is slidably mounted in a housing plate 18 constructed of heavy plate material and formed substantially U-shaped in cross section as shown in Fig. 4. A flat

bearing plate 19 is secured against the outer face of the door 11 and extends upwardly from the bottom edge of said door to the center thereof and the housing plate 18 rests against this plate and both are securely riveted to the rear face of the door by rivets 20.

The upper end of the bolt 17 is provided with a rectangular opening 21 and a pivotal arm 22 extends through this opening at right angles and is pivoted at 23 shown particularly in Fig. 1 to a bracket 24 riveted to the face of the door 11. The pivotal point 23 of arm 22 is positioned close to the opening or fulcrum point 21 shown in Fig. 3 of the arm and said arm extends outwardly therefrom to a position near the outer edge of the door and is provided at its outer end with a clevis 25 and chain 26, which chain is manually or otherwise actuated to release the bolt 17 from its engagement with the latch member 15.

A stop 27 in the form of a cotter pin is inserted through the bolt 17 above the housing plate and rests upon shims or spacers 28, said shims are U-shaped and embrace the bolt 17 and bear against the upper end of the said housing plate. The cotter pin 27 limits the downward movement of the bolt 17 and maintains the arm 22 in horizontal position when the door 11 is latched.

The guideway 29 formed between the housing plate 18 and bearing plate 19 is in vertical alignment with the opening 16 in the latch member and the lower end of the bolt 17 has a beveled end 30 adapted to engage the latch member opening to draw the door tightly against the dipper.

A plug 31 is tapped into the housing plate 18 and provides a means for oiling the guideway 29. The arm 22 and latch bolt 17 are constructed of heavy material and the relative arrangement thereof causes said bolt to gravitate to latched position when the chain is released and to remain normally in engagement with the latch member of the dipper.

Having thus described my invention, and an embodiment of it, in the full, clear and exact terms required by law, and knowing that it comprises novel, useful and valuable improvements in the art to which it pertains, I here state that I do not wish to be limited to the precise construction and arrangement of the several parts, as herein set forth, as the same may be variously

modified by a skilled mechanic without departing from the spirit and scope of my invention as defined in the appended claims.

What I claim and desire to secure by 5 Letters Patent of the United States, is the following, to-wit:

1. In a latch mechanism, the combination with a hinged door, a bolt for locking said door in a closed position, a plate adapted to 10 reinforce said door and prevent warping, means to insure the proper alignment of said bolt, said means consisting of a U-shaped housing in cross section, said plate and housing being bolted to said door, means 15 to operate said bolt consisting of an arm pivoted to said door and engaging a slot in said bolt and means to limit the downward movement of said bolt consisting of a cotter pin secured to said bolt and engaging 20 the housing thereof.

2. In a latch mechanism, the combination

with a hinged door, a bolt provided with a rectangular slot adapted to lock said door in a closed position, a plate adapted to reinforce said door and prevent warping, means 25 to insure the proper alignment of said bolt, said means consisting of a U-shaped housing in cross section and extending approximately to the length of said bolt, said plate and housing being bolted together to said door, 30 a pivoted arm engaging the rectangular slot of said bolt and adapted to operate said bolt, and means to limit the downward movement of said bolt consisting of U-shaped shims embracing said bolt and resting upon the 35 housing thereof, and a cotter pin inserted through the slot of said bolt and engaging said shims.

In testimony that I claim the foregoing I have hereto set my hand this 5th day of 40 Jan., 1924.

JOSEPH A. HUDNER.
